UNITED STATES PATENT OFFICE.

EDGAR E. TATLER, OF TRENTON, NEW JERSEY.

DESIGN FOR A PLATE OR SIMILAR ARTICLE.

Application filed September 8, 1923. Serial No. 7,162. Term of patent 7 years.

To all whom it may concern:

Be it known that I, EDGAR E. TATLER, a citizen of the United States, and a resident of Trenton, in the county of Mercer and State of New Jersey, have invented a new, original, and ornamental Design for a Plate or Similar Article, of which the following is a specification, reference being had to the

accompanying drawing, forming part thereof, which drawing is a face view of a plate or similar article illustrating my new design.

I claim:

The ornamental design for a plate or similar article, as shown.

EDGAR E. TATLER.
